Filed Mar. 30, 1967, Ser. No. 627,068
7 Claims. (Cl. 5-99)

ABSTRACT OF THE DISCLOSURE

A folding crib having a bottom wall hinged to swing upwardly against one side wall, and having end walls each composed of a series of three panels hingedly interconnected for relative pivotal movement about vertical axes, the panels at one side of the crib being rigidly connected to the corresponding side wall and the panels at the other side being hingedly connected to the corresponding side wall. Two of the panels of each end wall lie between the bottom wall and one side wall when the crib is folded. A guide means interconnecting the side walls guides same toward and away from each other in parallel relation when the bottom wall is in its retracted position. An actuating means connected to one side wall and to the guide means moves the side walls toward and away from each other, and locks the crib in its folded and unfolded positions.

Summary and objects of the invention

A general object of the invention is to provide a folding crib which folds easily into a compact package without the removal of any parts thereof, and which is automatically locked in either its folded or unfolded position.

More particularly, a primary object of the invention is to provide a folding crib having end walls each comprising a series of three panels hingedly interconnected for relative pivotal movement about vertical axes, the panels at one side of the crib being rigidly connected to the corresponding side wall thereof, and the panels at the opposite side of the crib being hingedly connected to the corresponding side wall thereof.

Another object is to provide a crib having a bottom wall pivotable upwardly into a retracted position between the rigid end-wall panels and adjacent the inner surface of the corresponding side wall of the crib. With this construction, the rigid end-wall panels and the corresponding crib side wall provide a compartment to receive the retracted bottom wall, while the other two panels of each end wall pivot inwardly into positions between the retracted bottom wall of the crib and the opposite side wall thereof. The end result is a very compact package for storage, transport, and the like, which is an important feature of the invention.

A further object of the invention is to provide guide means interconnecting the two side walls of the crib for guiding such side walls toward and away from each other while maintaining them in parallel relation at all times.

Still another object is to provide actuating means connected to the guide means for moving the side walls toward and away from each other, and for locking them in their relatively contracted and extended positions, so that the crib is automatically locked in its folded and unfolded positions.

Yet another object is to provide a folding crib of the foregoing nature wherein the guide means includes two guide links spanning the space between the side walls of the crib and having ends pivotally connected to the respective side walls, two track means respectively extending

2

longitudinally of the side walls for respectively guiding the other ends of the guide links longitudinally of the side walls, and means pivotally interconnecting the guide links intermediate their ends. With this construction, the two side walls of the crib are maintained in parallel relation at all times in their guided movement toward and away from each other.

10 An additional object is to provide such a folding crib wherein the actuating means for folding and unfolding the crib comprises an actuating lever pivotally connected to one of the side walls, and an actuating link having its ends respectively pivotally connected to the actuating lever and to one of the guide links.

15 The foregoing objects, advantages, features and results of the present invention, together with various other objects, advantages, features and results thereof which will be evident to those skilled in the folding crib art in the light of this disclosure, may be achieved with the exemplary embodiment of the invention described in detail 20 hereinafter and illustrated in the accompanying drawing.

Description of the drawing

In the drawing:
25 FIG. 1 is a side elevational view of a folding crib of the invention in its unfolded position;

FIG. 2 is an end elevational view taken as indicated by the arrowed line 2-2 of FIG. 1;

FIG. 3 is a sectional view taken as indicated by the arrowed line 3-3 of FIG. 1;

30 FIG. 4 is a view similar to FIG. 3, but showing the crib of the invention in its folded position;

FIG. 5 is an end elevational view similar to FIG. 2, but showing the crib in its folded position; and

FIG. 6 is an enlarged, fragmentary sectional view taken as indicated by the arrowed line 6-6 of FIG. 4.

Detailed description of the invention

Referring to the drawing, designated generally therein by the numeral 10 is a folding crib which embodies the invention and which includes horizontally spaced side walls 12 and 14, hereinafter referred to as front and rear walls, respectively. The front wall 12 includes vertically spaced, horizontally extending, upper and lower panels 16 and 18, the upper panel being hingedly connected to the lower panel by a horizontal hinge means 20, extending longitudinally of the front wall 12, so that the upper panel may be swung downwardly for easier access to the interior of the crib, as in attending to a baby therein, changing sheets, or the like. The hinge means 20 is shown as a piano hinge, but it will be understood that any other suitable type may be used.

40 The front wall 12 of the folding crib 10 includes two corner posts 22 at the respective ends thereof. The lower panel 18 of the front wall 12 is rigidly joined to the corner posts 22 in any suitable manner. The upper panel 16 may be latched to the corner posts 22 in any suitable manner, not shown. The rear wall 14 also includes corner posts 24 at its respective ends, the rear wall including an intermediate panel 26 of any suitable construction 45 rigidly connected at its ends to the corner posts 24. The front and rear corner posts 22 and 24 are provided at their lower ends with suitable casters 28, as is conventional.

45 The folding crib 10 includes two horizontally spaced end walls 30 each comprising horizontally spaced, vertically extending panels 32, 34 and 36. The panels 32 are rigidly connected to the corner posts 24 of the rear wall 14 in any suitable manner, the rear wall 14 and the panels 32 thus forming a rigid structure. The panels 34 50 are connected to the panels 32 by vertical hinge means 38 and the panels 36 are connected to the panels 34 by vertical hinge means 40. The panels 36 are also con-

nected to the front corner posts 22 by vertical hinge means 42. All of these hinge means are shown as piano hinges, but hinges of other suitable types may be used.

With the foregoing construction, the hinged panels 34 and 36 of the end walls 30 may be folded inwardly adjacent the front wall 12 of the crib 10, as illustrated in FIGS. 4 and 5 of the drawing. Thus, when in its folded position, the crib 10 forms a compact package for transport, storage, or the like.

The folding crib 10 includes a bottom wall 44 which, if desired, may take the form of a framed crib spring, not shown. The bottom wall 44 may also carry a crib mattress 46. A horizontal hinge means 48, parallel to the rear wall 14, pivotally connects one edge of the bottom wall 44 to the rigid structure formed by the rear wall 14 and the end panels 32. In the construction illustrated, the hinge means 48 comprises two longitudinally spaced hinges 50 interconnecting the bottom wall 44 and the end panels 32. With this construction, the bottom wall 44, and the mattress 46, may be pivoted upwardly into a retracted position wherein it is disposed adjacent and parallel to the inner surface of the rear wall 14, and between such rear wall and the inwardly-folded end panels 34 and 36 when the crib is in its folded position. In use, the edge of the bottom wall 44 opposite the hinged edge thereof rests on a support 52 carried by and extending longitudinally of the lower, fixed panel 18 of the front wall 12.

The folding crib 10 also includes a guide means 54 interconnecting the front and rear walls 12 and 14 for guiding same toward and away from each other in parallel relation, in folding and unfolding the crib, when the bottom wall 44 is in its retracted position. With this construction, the hinged end panels 34 and 36 fold inwardly between the front wall 12 and the bottom wall 44 when the bottom wall is in its retracted position and the front and rear walls are guided toward each other in parallel relation by the guide means 54.

The guide means 54, which is located below the operative position of the bottom wall 44, includes longitudinally-extending rail or track members 56 suitably rigidly connected to the lower panel 18 of the front wall 12 and the panel 26 of the rear wall 14. Two guide links 58 have ends respectively connected to the track members 56 by pivot means 60. The guide links 58 form an X and span the space between the track members 56 of the respective front and rear walls 12 and 14, being pivotally interconnected intermediate their ends by a pivot means 62. The other ends of the guide links 58 carry track following pins 64 disposed in and movable along longitudinally extending track slots 66 in the respective track members 56.

The foregoing construction of the guide means 54 provides a parallelogram-type linkage interconnecting the front and rear walls 12 and 14 of the folding crib 10 in such a manner that these walls are maintained in parallel relation at all times as they are moved toward and away from each other in folding and unfolding the crib. This will be apparent from a comparison of FIGS. 3 and 4 of the drawing.

The folding crib 10 includes an actuating means 68 connected to the guide means 54 for moving the front and rear walls 12 and 14 toward and away from each other. As best shown in FIGS. 3 and 4, the actuating means 68 includes an actuating lever 70 pivotally connected intermediate its ends, at 71, to one of the track members 56, preferably for track member on the front wall 12 of the crib 10 for maximum accessibility. An actuating link 72 has one end pivotally connected to one end of the actuating lever 70 at 74, and has its other end pivotally connected to one of the guide links 58, at 76, adjacent the track following pin 64 on that guide link. As will be apparent, by pivoting the actuating lever 70 from the position shown in FIG. 3 to that shown in FIG. 4, the crib 10 is folded. By pivoting the actuating lever in the opposite direction, the crib 10 is unfolded.

Considering the operation of the invention, it will be assumed that the crib 10 is in its unfolded position and is to be folded. The first step is to pivot the bottom wall 44 upwardly into its retracted position, as shown in FIGS. 4, 5 and 6. Then, the actuating lever 70 is pivoted from the position shown in FIG. 3 to that shown in FIG. 4, preferably after manually breaking the hinged joints represented by the hinge means 40 between the end panels 34 and the end panels 36. Such swinging of the actuating lever 70 through an angle of substantially 180° results in folding the hinged end panels 34 and 36 inwardly between the front wall 12 of the folding crib 10 and the retracted bottom wall 44 thereof, as shown in FIGS. 4, 5 and 6 of the drawing. Unfolding of the crib 10 may be effected essentially by reversing the foregoing operation.

Although an exemplary embodiment of the present invention has been disclosed herein for purposes of illustration, it will be understood that various changes, modifications and substitutions may be incorporated in such embodiment without departing from the spirit of the invention as defined by the claims appearing hereinafter.

We claim as our invention:

1. In a folding crib, or the like, the combination of:

- (a) two horizontally spaced side walls;
- (b) two horizontally spaced end walls each comprising horizontally spaced, vertically extending, first, second and third panels;
- (c) said first panels of said end walls being rigidly connected to one of said side walls at the respective ends thereof;
- (d) two vertical hinge means respectively pivotally connecting said third panels of said end walls to the other of said side walls at the respective ends thereof;
- (e) other vertical hinge means respectively pivotally connecting said second panels of said end walls to said first and third panels thereof;
- (f) a bottom wall;
- (g) horizontal hinge means, parallel to said side walls, for pivotally connecting one edge of said bottom wall to the rigid structure formed by said one side wall and said first panels of said end walls; and
- (h) whereby said bottom wall may be pivoted upwardly into a retracted position between said first panels of said end walls and adjacent and parallel to the inner surface of said one side wall.

2. A folding crib, or the like, as set forth in claim 1, including:

- (a) guide means interconnecting said side walls for guiding same toward and away from each other in parallel relation when said bottom wall is in its retracted position; and
- (b) whereby said second and third panels of said end walls pivot inwardly between said other side wall and said bottom wall when said bottom wall is in its retracted position and said side walls are guided toward each other in parallel relation by said guide means.

3. A folding crib, or the like, according to claim 2, including actuating means connected to said guide means for moving said side walls toward and away from each other.

4. A folding crib, or the like, as defined in claim 3, wherein said guide means includes:

- (a) two guide links spanning the space between said side walls;
- (b) two pivot means respectively connecting corresponding ends of said guide links to said side walls;
- (c) two track means respectively extending longitudinally of said side walls for respectively guiding the other ends of said guide links longitudinally of said side walls; and
- (d) another pivot means pivotally interconnecting said guide links intermediate their ends.

5. A folding crib, or the like, as set forth in claim 4, wherein said actuating means includes:

- (a) an actuating lever pivotally connected to one of said side walls; and
- (b) an actuating link having its ends respectively pivotally connected to said actuating lever and one of said guide links.

6. A folding crib, or the like, according to claim 5, wherein said track means comprise track members respectively having track slots therein which receive track following pins on said other ends of said guide links.

7. A folding crib, or the like, as defined in claim 6,

wherein said horizontal hinge means pivotally connects said bottom wall to said first panels of said end walls.
